Fig. 4.

UNITED STATES PATENT OFFICE.

ROBERT LESLIE BELLHOUSE, OF MANCHESTER, ENGLAND, ASSIGNOR TO THE FINE COTTON SPINNERS & DOUBLERS ASSOCIATION LIMITED, OF MANCHESTER, ENGLAND.

COMBING MACHINE.

Application filed April 24, 1928, Serial No. 272,514, and in Great Britain June 18, 1927.

This invention relates to combing machines of the Nasmith type and more particularly to the improvements in the weighting of the top detaching rollers thereof of the 5 type in which a weight is suspended directly from the detaching roller weight hook by a main wire and is held forward out of contact with the beam by a second wire.

According to the invention the effective 10 weight on the rollers is made adjustable either by attaching the main wire carrying the weight at different distances from the pivotal centre of the hook or by attaching the end of the second wire at different positions 15 to alter the angle of such wire with the horizontal so that with a constant weight on the end of the main wire, the effective weight on the rollers can be adjusted.

The invention will be described with reference 20 to the accompanying drawings:—

Fig. 1 is a view of one form of the invention showing the detaching roller weight hook in position for applying weight to the roller.

Fig. 2 is a view of the same form of the invention showing the detaching roller weight hook in position with the weight relieved from the roller.

Fig. 3 is a view of another form of the invention showing the detaching roller weight hook in position for applying weight to the roller.

Fig. 4 is a view of this second form of the invention showing the detaching roller weight hook in position with the weight relieved from the roller.

In the form of the invention shown in Figs. 1 and 2 the detaching roller weight hook A is provided with a projection B having a number of apertures b at different distances from the pivotal centre a of the hook, in which apertures the end of the main wire C carrying the weight W can be attached.

The end of the second wire D by which the 45 weight W is held forward out of contact with the beam E instead of being attached to a fixed point, is attached to a pivoted arm or lever F so that as the detaching roller weight hook A moves upwards, the end of the second wire D will move upwards approximately the same distance so that with whatever aperture b the end of the main weight carrying wire C may be in engagement, the weight will be able to follow the upward movement

of the hook. The pivoted arm or lever F to 55 which the end of the wire D is attached is preferably the operating lever of the weight releasing motion. The latter consists of a bell-crank or two armed lever F pivoted on a bracket e carried by the beam E. The upper 60 arm of the lever is pivotally attached to a connecting arm F^1 forked or slotted at its upper end and engaging a pin a^1 carried on the hook A. The lower arm of the lever F serves as an operating handle for raising the 65 detaching roller weight hook A.

The weight W may be attached directly to the lower end of the main weight carrying wire or it may be connected thereto by a third wire suspended vertically from the end 70 thereof.

In the form of the invention shown in Figs. 3 and 4 the adjustment is effected by attaching the wire D at different points in front of the beam E and below the tube to alter the 75 angle of the wire D with the horizontal, since the more nearly the wire D approaches the horizontal, the greater will be the effective weight on the detaching roller weight hook.

The attaching points may be arranged on 80 a fixed bracket but they are preferably arranged as shown at f^1 , f^2 and f^3 on the pivoted bell-crank weight relieving lever F of the construction described above as such arrangement affords a wider range of adjustment. 85

A suitable projection B is formed on the detaching roller weight hook A so that the main wire C which carries the weight W may be attached to it at a point which will 90 afford the necessary leverage for a given weight (say 25 lbs.) to give the minimum weight required when the second wire D which holds the weight forward away from the beam is anchored at its uppermost point 95 f^1 of attachment.

In Figs. 3 and 4 the effective weight on the detaching rollers H is greatest when the second wire D which holds the weight forward away from the beam is horizontal and 100 decreases as such wire approaches the vertical.

If desired the two forms of the invention described in the foregoing may be combined, this giving a very much wider range of adjustment. 105

What I claim as my invention and desire to protect by Letters Patent is:—

1. In weighting mechanism of the type referred to for the top detaching rollers of combing machines of the Nasmith type the combination with the detaching roller weight hook and a weight of a wire carrying the weight, a second wire attached to the first wire to hold the weight out of contact with the beam and means for varying the effective weight on the detaching rollers.
- 10 2. In weighting mechanism of the type referred to for the top detaching rollers of combing machines of the Nasmith type the combination with the detaching roller weight hook and a weight of a wire carrying the weight, a second wire attached to the first wire to hold the weight out of contact with the beam, a projection on the detaching roller weight hook and apertures in the projection at different distances from the pivot thereof so that the effective weight on the detaching rollers can be varied.
- 15 3. In weighting mechanism of the type referred to for the top detaching rollers of combing machines of the Nasmith type the combination with the detaching roller weight hook and a weight of a wire carrying the weight, a second wire attached to the first wire to hold the weight out of contact with the beam, a bracket mounted on the beam, a lever mounted on the bracket and extending forward from the beam and attaching points on the lever at different heights to which the end of the second wire can be anchored so that the angle of the wire can be altered to vary the effective weight on the detaching rollers.
- 20 4. In weighting mechanism of the type referred to for the top detaching rollers of combing machines of the Nasmith type the combination with the detaching roller and a weight attached to the first wire to hold the weight out of contact with the beam, a bracket mounted on the beam, a weight releasing lever pivotally mounted on the bracket and extending forward from the beam and devices on the lever at different heights to which the end of the second wire can be anchored so that the angle of the wire can be altered to vary the effective weight on the detaching rollers.
- 25 5. In weighting mechanism of the type referred to for the top detaching rollers of combing machines of the Nasmith type the combination with the detaching roller and a weight attached to the first wire to hold the weight out of contact with the beam, a bracket mounted on the beam, a weight releasing lever pivotally mounted on the bracket and extending forward from the beam and devices on the lever at different heights to which the end of the second wire can be anchored so that the angle of the wire can be altered to vary the effective weight on the detaching rollers.
- 30

vary the effective weight on the detaching 35 rollers.

4. In weighting mechanism of the type referred to for the top detaching rollers of combing machines of the Nasmith type the combination with the detaching roller weight hook and a weight of a wire carrying the weight, a second wire attached to the first wire to hold the weight out of contact with the beam, a bracket mounted on the beam, a lever pivotally mounted on the bracket 40 and extending forward from the beam and attaching points on the lever at different heights to which the end of the second wire can be anchored so that the angle of the wire can be altered to vary the effective 45 weight on the detaching rollers.

5. In weighting mechanism of the type referred to for the top detaching rollers of combing machines of the Nasmith type the combination with the detaching roller and a weight attached to the first wire to hold the weight out of contact with the beam, a bracket mounted on the beam, a weight releasing lever pivotally mounted on the bracket and extending forward from the beam and devices on the lever at different heights to which the end of the second wire can be anchored so that the angle of the wire can be altered to vary the effective weight 50 on the detaching rollers.

In testimony whereof I have hereunto set my hand.

ROBERT LESLIE BELLHOUSE.
